UNITED STATES PATENT OFFICE.

JOHN STOCK, OF DUNTON, NEW YORK, ASSIGNOR TO INTERSTATE ELECTRIC NOVELTY COMPANY, OF NEW YORK, N. Y., A CORPORATION OF NEW YORK.

ELECTRIC POCKET-LAMP.

1,158,081.

Specification of Letters Patent. Patented Oct. 26, 1915.

Application filed April 2, 1915. Serial No. 18,685.

To all whom it may concern:

Be it known that I, JOHN STOCK, a subject of the Emperor of Austria-Hungary, residing at Dunton, Long Island, Queens county, State of New York, have invented 5 certain new and useful Improvements in Electric Pocket-Lamps, of which the following is a full, clear, and exact description.

This invention relates to an improvement 10 in electric pocket-lamps, but pertains more particularly to a circuit closer for such lamps to complete the circuit between the battery and the lamp.

The class of pocket-lamps to which my 15 improvement is more particularly applied is of that type consisting of a tubular casing arranged to retain an electric battery and lamp, the circuit for said lamp being closed by means arranged for manipulation exteriorly of the casing.

I will now proceed to describe my invention in detail, the essential features of which will be summarized in the appended claims, 20 reference being had to the accompanying drawing, forming part hereof; wherein—

Figure 1 is a side elevation of a pocket-lamp embodying my improvement; Fig. 2 is a rear elevation thereof; Fig. 3 is an enlarged fragmentary side elevation, partly 25 in section, of one end of the device; Fig. 4 is sectional view of the bushing which carries the contacts for the lamp circuit; Fig. 5 is a sectional view, the section being taken on a line 5—5 in Fig. 3; and Fig. 6 is a fragmentary side elevation showing a modified 30 form of my invention.

Referring to the drawing, the casing of my improved lamp is indicated by 1, within which is mounted the usual battery 2 which 40 supplies current for a lamp 3. One leg of the circuit consists of the casing 1 with which the lamp 3 is placed in circuit in the usual manner. The other leg of the circuit for the lamp is completed by a circuit-closer 45 in circuit with a spring 4 which, at one end bears against one end of the battery 2. The other end of the battery bears against the end of the lamp 3 as is usual in this type of lamp.

50 My improvement pertains more particularly to the circuit-closer and mounting for the contact-spring 4. It is usual to place a contact-spring, such as 4, in one end of a

casing and to have a battery bearing against said spring; but to more fully insulate the 55 spring from the casing I provide a rubber or fiber bushing 5 having a pocket 6 which retains the spring 4, the said bushing being inserted in the open end of the casing, as shown in Fig. 3, and held therein by a set- 60 screw 7.

To convey the current from the spring 4 to the circuit-closer, I provide a conducting strip 8 having one of its ends located in the pocket 6, the other end being bent upwardly, 65 as at 9, to form a stop or contact, the said contact being located in a recess 10 cut in the wall of the bushing 5. (See Figs. 3 and 4). To close the circuit between the casing 1 and battery, I provide a metallic 70 circuit-closer 11 which is arranged to be moved longitudinally of the casing 1, the said circuit-closer being mounted upon or carried by the flattened portion 12 of the bushing 5, the inner end of the circuit-closer 75 11 being bent inwardly to form a contact 13 to engage the contact 9 on the conductor 8. The opposite end of the circuit-closer 11 is passed through an opening 13^a in the casing 1 and extends beyond said opening sufficiently to enable one to operate same. To facilitate operating the circuit-closer 11, a rounded projection 14 may be provided. When the circuit-closer is pushed or moved outwardly the contacts 9 and 13 will come 80 together, thereby closing the circuit for the lamp 3. When the circuit-closer is pushed inwardly, the circuit for the lamp will be opened. The circuit-closer 11 is not in any 85 way secured or connected to the casing, but is free to be moved longitudinally thereof, a portion of the circuit-closer being within the casing and the remainder located exteriorly of the casing.

To hold the lamp in a pocket I may employ a clip, such as indicated by 15 in Fig. 1; or I may extend the circuit-closer 11 sufficiently beyond the opening 13 to provide a resilient clip 16 as shown in the modified 95 form of my improvement illustrated in Fig. 6. In this latter instance a rounded head 17 will be located upon the under surface of the clip 17 to bear against the casing 1. This latter form of my invention possesses 100 the advantage of automatically opening the 105 circuit for the lamp when the casing is

placed in a pocket, for the reason that the action of forcing the clip over the material of the pocket, will move the circuit-closer rearwardly, thereby opening the circuit for the lamp 3. It will also be seen by referring to Figs. 3 and 4 that the bushing 5 is provided with a counterbore 18 to receive the inner end of the battery 2. By this means the battery is prevented from lashing in the casing and thus breaking the covering thereof, which is usually of relatively thin paper. Furthermore the counterbore 18 acts to keep the battery 2 and spring 4 in alinement.

15 Having now described my invention what I claim and desire to secure by Letters Patent is:

1. A pocket-lamp, consisting of a casing, a lamp located at one end thereof, a battery within said casing but insulated therefrom and having one of its ends in contact with said lamp, the other side of the circuit for said lamp being through said casing, a bushing of insulating material located in the opposite end of said casing, a spring within said bushing bearing against the adjacent end of said battery, a longitudinally slideable circuit-closer located between said bushing and said casing and one end of which extends exteriorly of the latter, and means to conduct current from said spring to a point adjacent said circuit-closer.

2. A pocket-lamp, consisting of a casing, a lamp located at one end thereof, a battery within said casing but insulated therefrom and having one of its ends in contact with said lamp, the other side of the circuit for said lamp being through said casing, a bushing of insulating material located in the opposite end of said casing, a spring within said bushing bearing against the adjacent end of said battery, a longitudinally slideable circuit-closer located between said bushing and said casing and one end of which extends exteriorly of the latter, a conductor carried by said bushing having one of its ends located adjacent said circuit-closer and arranged to contact therewith, the opposite end of said conductor being in contact with said spring.

3. A pocket-lamp, consisting of a casing, a lamp located at one end thereof, a battery within said casing but insulated therefrom and having one of its ends in contact with said lamp, the other side of the circuit for said lamp being through said casing, a bushing of insulating material located in the opposite end of said casing, said bushing being provided with a pocket, and a counterbore in communication therewith to receive the inner end of said battery, a spring, located in said pocket, bearing against the end of the battery within said counterbore, a conductor carried by said bushing and projecting into said pocket and

contacting with the spring therein, the other end of said conductor passing through the wall of said bushing, and a circuit-closer operable exteriorly of the casing to close the circuit between said casing and said conductor.

4. A pocket-lamp, consisting of a casing, a lamp located at one end thereof, a battery within said casing but insulated therefrom and having one of its ends in contact with said lamp, the other side of the circuit for said lamp being through said casing, a bushing of insulating material located in the opposite end of said casing, said bushing being provided with a pocket and a counterbore in communication therewith to receive the inner end of said battery, a spring, located in said pocket, bearing against the end of the battery within said counterbore, a conductor carried by said bushing and projecting into said pocket and contacting with the spring therein, the other end of said conductor passing through the wall of said bushing, and a longitudinally movable circuit closer located between said casing and said bushing, to close the circuit between said casing and said conductor.

5. A pocket-lamp, consisting of a casing, a lamp located at one end thereof, a battery within said casing but insulated therefrom and having one of its ends in contact with said lamp, the other side of the circuit for said lamp being through said casing, a bushing of insulating material located in the opposite end of said casing, said bushing being provided with a pocket, and a counterbore in communication therewith to receive the inner end of said battery, a spring, located in said pocket, bearing against the end of the battery within said counterbore, a conductor carried by said bushing and projecting into said pocket and contacting with the spring therein, the other end of said conductor passing through the wall of said bushing and projecting into a recess in said wall, the outer end of said conductor being turned upwardly to form a contact, and a longitudinally movable circuit-closer located between said bushing and said casing, the inner end of said circuit-closer being turned downwardly to form a contact to impinge upon the contact of said conductor, the outer end of said circuit-closer passing through an opening in said casing.

6. A pocket-lamp, consisting of a casing, having a constricted portion, a lamp located at one end thereof, a battery within said casing, means to establish a circuit between said lamp and said battery, and a circuit-closer included in said circuit, consisting of a longitudinally slideable strip, the free end of which constitutes a retaining clip, a portion of said slideable strip being located within the larger portion of the casing and

passing out through the wall thereof to overlap the constricted portion of the casing.

7. A pocket-lamp consisting of a casing, a lamp located at one end thereof, a battery within the casing, a circuit closer consisting of a longitudinally slidable-strip carried by the casing, a bushing, having a pocket, within the casing to retain the circuit closer in position, and a strip of conducting

material located in said pocket arranged to close the circuit between said battery and said slidable-strip.

Signed at New York city, N. Y. this 30 day of March 1915.
